COMBINED FOOTSTOOL AND RECEPTACLE
FOR SEWING ARTICLES

Ernest J. Hubbert, Kansas City, Mo.

Application November 28, 1949, Serial No. 6,306

Term of patent 14 years

(Cl. D15—8)

To all whom it may concern:

Be it known that I, Ernest J. Hubbert, a citizen of the United States of America, and a resident of Kansas City, Jackson County, State of Missouri, have invented a new, original, and ornamental Design for a Combined Footstool and Receptacle for Sewing Articles, of which the following is a specification, reference being had to the accompanying drawing, forming a part thereof.

In the drawing,

Figure 1 is a perspective view of a combined footstool and receptacle for sewing articles, with the lid in open position, showing my new design.

Fig. 2 is a rear perspective view of said combined footstool and receptacle for sewing articles, with the lid in closed position.

I claim:

The ornamental design for a combined footstool and receptacle for sewing articles, substantially as shown.

ERNEST J. HUBBERT.
